UNITED STATES PATENT OFFICE.

JACOB ZIEGLER, OF COFFEYVILLE, KANSAS.

HARNESS-TRACE.

SPECIFICATION forming part of Letters Patent No. 727,730, dated May 12, 1903.

Application filed March 27, 1902. Serial No. 100,248. (No model.)

To all whom it may concern:

Be it known that I, JACOB ZIEGLER, a citizen of the United States, residing at Coffeyville, in the county of Montgomery and State 5 of Kansas, have invented a new and useful Harness-Trace, of which the following is a specification.

The present invention relates to harness-traces; and the object thereof is to improve 10 and simplify this class of structures.

In a patent granted to me on September 6, 1892, and numbered 482,289 there is disclosed a buckle designed especially for adjustably connecting the trace-strap and hame-tug. In 15 that structure a buckle-frame is provided that is detachably and adjustably secured to one strap by means of a projecting stud and is provided with forwardly-extending forked fingers which are engaged by a loop attached 20 to the end of the other strap to be held. The great objection to this structure has been that the entire strain is transmitted by the loop through the frame and to the stud, thereby causing either the breakage of the 25 latter or the tearing out of the hole in which it is placed. Now one of the very important objects of this invention is to improve this structure by constructing the frame so that the loop will transmit a portion of the strain 30 directly to the strap, and thereby relieve the stud of the same.

Another important object is to provide a novel and inexpensive connection between the trace-strap and hame-tug, so that there 35 will be no projecting or free ends when the trace is lengthened or shortened.

The means for accomplishing these objects is illustrated in the accompanying sheet of drawings and described in the following 40 specification.

In said drawings, Figure 1 is a perspective view of a portion of a trace constructed in accordance with the present invention. Fig. 2 is a longitudinal section through the buckle connection. Figs. 3 and 4 are perspective views of the two buckle members. Fig. 5 is a perspective view of the guide-frame employed.

Similar numerals of reference designate corresponding parts in all the figures of the drawings.

The trace consists of a hame-tug 10 and the

trace-strap 11, the adjacent ends of which are arranged in overlapping relation, the hame-tug being provided with a plurality of 55 openings 12. Secured to the overlapping ends of the tug and strap are loops 13 and 14, the loop 13 of the tug being in the form of a guide-frame, through which is slidably passed the trace-strap, and said guide-frame is preferably provided with side eyes, as 15.

The loop 14, secured to the end of the trace-strap, constitutes one member of the buckle and comprises side bars 14^a, provided with inturned terminals having sockets 14^b in their 65 inner faces and connected at their extremities by cross-bars 14^c and 14^d. This loop is now made of a single piece, whereas in the former structure it was constructed of separate sections. The sockets 14^b are arranged 70 at an inclination to the side bars, or, in other words, diagonally across the inner faces of said bars, as clearly shown in Fig. 2. The other member of the buckle is in the form of a frame made up of side bars 16, a transverse 75 offset end bar 17 to form a strap-receiving loop, and an intermediate cross-bar 18, that is provided with a projecting stud 19, arranged to engage in the openings 12 of the tug. The portions of the side bars 16 which 80 project beyond the cross-bar 18 constitute fingers 20, which are located in angular relation to the main body of the frame and to the hame-tug, passing diagonally across the side edges of the latter and in the sockets 14^b of 85 the side arms, said fingers having inwardly-bent terminal stop-hooks 21, that engage on opposite sides of the strap, as shown in Figs. 1 and 2. The under faces of these fingers 20 are smooth, and the cross-bar 14^c of the loop 90 is therefore engaged wholly within the same and clamped between them and the hame-tug, as clearly illustrated in Figs. 1 and 2, said hooks encircling the end bar to prevent movement of the same in either direction. 95

It will be seen that by this construction the strain transmitted to the loop 14 will cause the cross-bar 14^c of said loop to wedge tightly between the fingers 20 and the hame-tug, thus dividing the strain and transmitting a great portion thereof to said hame-tug, thereby relieving the stud 19 of the same, this action being obtained by the inclined relation of the fingers 20 and the inclined dispo- 100

sition of the sockets 14^b, through which said fingers pass. The inwardly - turned stop-hooks 21, engaging over the sides of the strap, prevent the accidental displacement of the 5 loop when the trace becomes slack, and thus prevents the unfastening of the same. Should it become desirable to shorten or lengthen the trace, it is only necessary to disengage the loop 14 from the buckle-frame and move 10 said frame until the stud 19 can be engaged in another opening. It will be observed that this structure is very simple, and as both of the overlapping ends are secured to the adjacent strap there will be no free or loose ends 15 even when the trace is shortened to its fullest extent. The structure is less expensive than the arrangement now ordinarily employed, in which a buckle is secured to the end of the hame-tug and the trace-strap is 20 adjustably secured to this buckle.

From the foregoing it is thought that the construction, operation, and many advantages of the herein-described invention will be apparent to those skilled in the art with- 25 out further description, and it will be understood that various changes in the size, shape, proportion, and minor details of construction may be resorted to without departing from the spirit or sacrificing any of the advantages, 30 of the invention.

Having thus described my invention, what I claim as new, and desire to secure by Letters Patent, is—

1. In a buckle of the class described, the 35 combination with a loop arranged to be secured to a strap and comprising side bars having inturned ends connected by a cross-bar, said inturned ends having inclined sockets at their inturned ends that extend diagonally 40 across the inner faces of the said bars, and a frame arranged to be secured to another strap

and having forwardly-projecting inclined side fingers that extend diagonally across the side edges of the strap and through the sockets of the side bars, said fingers extending over the 45 cross-bar of the loop and having smooth under faces, whereby said cross-bar will be clamped between said fingers and the strap held thereby.

2. In a buckle of the class described, the 50 combination with a loop arranged to be secured to a strap and comprising side bars having inturned ends connected by a cross-bar, and a frame arranged to be secured to another strap and having forwardly-projecting 55 inclined side fingers that extend diagonally across the edges of the strap, said fingers extending over the cross-bar of the loop and having smooth under faces, and being furthermore provided with terminal hooks that embrace the cross-bar and engage over the side edges of the strap, whereby said cross-bar will be clamped between said fingers and the strap held thereby.

3. In a device of the class described, the 60 combination with the loop 14 composed of side and end bars and provided with inclined sockets at the junction of the side and one end bar, of the frame composed of side bars, an offset end bar, and an intermediate cross- 65 bar carrying a stud, the side bars being inclined to form fingers which coöperate with the sockets of the loop, and stop-hooks at the ends of the side bars.

In testimony that I claim the foregoing as 70 my own I have hereto affixed my signature in the presence of two witnesses.

JACOB ZIEGLER.
